ELECTRON BEAM-TUNING-INDICATION TUBE

Horst Edgar John Heinrich Stietzel, Hamburg, and Alexander Hans Adolf Siebenberg, Hamburg-Fuhlsbuttel, Germany, assignors, by mesne assignments, to North American Philips Company, Inc., New York, N. Y., a corporation of Delaware

Application November 13, 1952, Serial No. 320,166

Claims priority, application Germany March 20, 1952

5 Claims. (Cl. 313—107.5)

The invention relates to a cathode-ray tube for tuning indication, having shadow angles or the like controlled by deflection rods and, if desired, an amplifying system housed in the same bulb.

Such tuning indicators have been known for a long time and efforts have been made to construct these tubes in order to obtain an optimum distinctness of indication or an optimum sensitivity, in a manner such that in the event of complete control they produce a maximum shadow angle.

For this purpose it has been suggested to provide a counter-electrode or counter-electrodes, preferably being at the potential of the luminescent screen, in the proximity of the cathode in a manner such that a strong and extensive field is produced between the cathode and the counter-electrode and between the deflection electrode and counter-electrode.

This construction has a limitation in that these counter-electrodes themselves project shadow sectors onto the screen, these sectors having a constant width, so that the useful screen surface is reduced. Efforts have been made to obviate this limitation by arranging the cathode with the associated electrodes eccentrically within the tube or to the luminescent screen. Thus, however, the second shadow sector produced in the case of concentrical arrangement is lost; this sector contributed effectively to enhance the tuning indication. Moreover, also for structural reasons this arrangement is not very favourable.

The invention obviates this disadvantage and consists in that the equipotential lines of the electric field between the screen and the cathode are made substantially elliptical in form by a shaping of the parts of the system at the potential of the screen, without introducing additional electrodes.

An efficient embodiment of the tuning indicator according to the invention consists in that the elliptical shape of the equipotential lines is obtained by means of a rotational-unsymmetrical shape of the screen, the circumference of which varies periodically. In other words, the shape of the screen is not a surface of revolution.

It is advisable to use a funnel-shaped luminescent screen, the cross-sectional area of which is oval and which has angles of different slopes, which are flatter in the direction of the long axis, on which the deflection rods are also located, and which extend more steeply in the direction of the short axis.

A further advantageous embodiment consists in that the funnel-shaped luminescent screen is substantially circular and has lines of inclination which extend with uniform steepness in the direction through the control-rods and extend first flatly towards the inside then gradually more steeply in the direction at right angles thereto. In this case, however, the light distribution of the luminescent surface may lack uniformity.

This is avoided, if the funnel-shaped screen has a circular cross-sectional area and lines of inclination which extend first steeply towards the inner side in the direction through the control-rods and then extend gradually more

2

flatly, but exhibit a constant slope in the direction at right angles thereto.

The elliptical shape of the equipotential lines may be obtained not only by a corresponding shape of the luminescent screen, but also by suitable shape of the cathode hood, which has to screen principally the light emanating from the incandescent cathode and is usually at the potential of the screen. As an alternative, these two measures may be combined, so that they support one another. To this end, it is desirable to shape the cathode hood, which is at the potential of the screen, in the form of a cup having a short, substantially cylindrical wall, which is provided with recesses at the areas near the control-rods.

In order that the invention may be readily carried into effect, it will now be described in detail with reference to the accompanying drawing.

Figs. 1 and 2 show the electric field in the shape of equipotential lines in a tuning indicator of conventional construction.

Figs. 3 and 4 show the same in a tuning indicator according to the invention.

Figs. 5, 6 and 7 show each a plan view at the upper left of the figure and two side views below and to the right of the plan view of three embodiment of a luminescent screen of a tube according to the invention.

Fig. 8 shows a cathode hood having recesses in accordance with the invention.

Figs. 1 and 2 show the equipotential lines of the electric field between the cathode 2, which is surrounded by a grid 1, and the luminescent screen 3 in a tuning indicator of conventional construction; the control-rods are designated by 4. If the control-rods are at cathode potential, the form of the equipotential lines is that shown in Fig. 1. If the rods are substantially at the potential of the luminescent screen, the shape of the equipotential lines shown in Fig. 2 is obtained. The electrons emanating from the cathode 2 first follow the lines at right angles to the equipotential lines and then extend straight on. In this way are produced the boundaries of the shadow sectors shown in dotted lines in Figs. 1 and 2.

The same is shown in Figs. 3 and 4 for an indicator tube according to the invention; the same reference numerals are used in these figures. It is assumed in the first place that the equipotential lines have the elliptical shape shown in Fig. 3 when the control-rods 4 are at cathode potential, though the means for obtaining this form are not shown. The deformation of the equipotential lines for the case in which the control-electrodes 4 are substantially at the potential of the luminescent screen is shown in Fig. 4. A comparison between Figs. 1 and 3 shows that, owing to the elliptical shape of the equipotential lines, a materially larger shadow angle is obtained.

In order to obtain such elliptical equipotential lines, use may be made of a luminescent screen as shown in Fig. 5. As is shown, the upper wider portion of the luminescent screen 3 is oval in shape, the aperture at the bottom of this funnel-shaped screen being, as usual, circular. In this aperture are shown the two control-rods 4, the cathode 2 being, of course, at the center and coaxially within the screen 3. The associated lateral views, below and to the right of the plan view, show that the angles of inclination of this funnel have different steepnesses; they are flatter in the direction of the long axis of the ellipse, and steeper in the direction of the short axis. The lateral views shown are almost identical to cross-sectional views through the screen along the major and minor axes of the oval screen 3. These cross-sectional views would correspond to the intersections of the screen with orthogonal planes having the screen axis as their line of intersection. As will be noted, these two intersections, i. e., the side views shown in the drawing,

are different, which means that the screen 3 is not a surface of revolution.

A further embodiment of such a luminescent screen is shown in Fig. 6. The luminescent screen 3 is, in this case, circular, so that the spectator observes the conventional circular shape and, moreover, the circular sectional area of the bulb is satisfactorily utilized. In order to obtain in this case an elliptical field of equipotential lines, the angles of inclination of the funnel are slightly shortened in the direction of the axis $x-x$, as is evident from the associated later or side view. That is, these side portions of the screen are concave instead of straight. In the direction of the axis $y-y$ the angle of inclination is straight, as is evident from the associated lateral view. With respect to the profile of inclination, a uniform transition exists between these two axes.

A further possible shape of the luminescent screen is shown in Fig. 7. Here again the screen is circular, but the lines of inclination are straight in the direction of the axis $x-x$, and in the direction of the axis $y-y$, the steepness varies in a sense contrary to that of the embodiment described in Fig. 6. That is, the side portions are convex instead of concave. The shape of the lines of inclination is evident from the associated lateral views.

According to the invention, an elliptical field is obtainable by using luminescent screens having the common feature that use is made of rotational-unsymmetrical bodies. However, the cathode hood, which primarily serves to screen the light emanating from the cathode, may also be utilized to obtain an electric field of this shape. This hood usually is at the potential of the luminescent screen, and, since in comparison with the conventional electrode system, this hood has appreciable dimensions, it exerts a marked influence on the shape of the electric field. A suitable embodiment of such a hood is shown in Fig. 8. This hood comprises a cylindrical wall 5 of comparatively small height, closed at the top by a slightly arcuate bottom 6 and supported by stay wires 7. The lower edge of the wall 5 is provided with recesses 8 at two areas diametrically opposite one another; these recesses produce an elliptical deformation of the electric field. It is advantageous to use a cathode hood as shown in Fig. 8 in conjunction with a luminescent screen as shown in any of the preceding embodiments, in order to have the effects of the two parts support one another.

As indicated earlier, the different cross-sectional views of the screen, made by the orthogonal planes, indicate a screen construction that distorts what was primarily a field with circular equipotential lines to one with mainly elliptical equipotential lines, which, as illustrated in Figs. 3 and 4, results in a wider shadow region with the minimum signal.

What we claim is:

1. A cathode-ray tuning indicator tube comprising a hollow, luminescent screen, a cathode arranged centrally and coaxially within the luminescent screen, and means including deflection members disposed between the cathode and screen for controlling, by its potential, the extent of fluorescence of the screen and arranged to provide two opposed fluorescent areas on the screen, the intersections of orthogonal planes, having the axis of the screen as their line of intersection, with the screen being different, whereby said screen has a shape different from a surface of revolution and the equipotential lines of the electric field established between cathode and screen when a potential difference is applied therebetween are strongly elliptical in shape.

revolution and the equipotential lines of the electric field established between cathode and screen when a potential difference is applied therebetween are strongly elliptical in shape.

5 2. A tube as set forth in claim 1, wherein a cup-like member surrounds an end of the cathode, said member having recessed portions in opposed side walls.

10 3. A cathode-ray tuning indicator tube comprising a funnel-like, hollow, luminescent screen having an oval cross-section with a long axis in one direction and a short axis at right angles thereto, a cathode arranged centrally and coaxially within the luminescent screen, and means including deflection members disposed along the long axis of the oval and between the cathode and screen for controlling, by its potential, the extent of fluorescence of

15 the screen and arranged to provide two opposed fluorescent areas on the screen, the intersections of orthogonal planes, having the axis of the screen as their line of intersection, with the screen being different, whereby said screen has a shape different from a surface of revolution and the equipotential lines of the electric field established between cathode and screen when a potential difference is applied therebetween are strongly elliptical in shape.

20 4. A cathode-ray tuning indicator tube comprising a funnel-like, hollow, luminescent screen, a cathode arranged centrally and coaxially within the luminescent screen, and means including deflection members disposed between the cathode and screen for controlling, by its potential, the extent of fluorescence of the screen and arranged to provide two opposed fluorescent areas on the screen, said funnel-like screen having concave portions on opposed side walls so that the intersections of orthogonal planes, having the axis of the screen as their line of intersection, with the screen are different, whereby said screen has a shape different from a surface of revolution and the equipotential lines of the electric field established between cathode and screen when a potential difference is applied therebetween are strongly elliptical in shape.

25 5. A cathode-ray tuning indicator tube comprising a funnel-like, hollow, luminescent screen, a cathode arranged centrally and coaxially within the luminescent screen, and means including deflection members disposed between the cathode and screen for controlling, by its potential, the extent of fluorescence of the screen and arranged to provide two opposed fluorescent areas on the screen, said funnel-like screen having convex portions on opposed side walls so that the intersections of orthogonal planes, having the axis of the screen as their line of intersection, with the screen are different, whereby said screen has a shape different from a surface of revolution and the equipotential lines of the electric field established between cathode and screen when a potential difference is applied therebetween are strongly elliptical in shape.

30 40 6. A cathode-ray tuning indicator tube comprising a funnel-like, hollow, luminescent screen, a cathode arranged centrally and coaxially within the luminescent screen, and means including deflection members disposed between the cathode and screen for controlling, by its potential, the extent of fluorescence of the screen and arranged to provide two opposed fluorescent areas on the screen, said funnel-like screen having convex portions on opposed side walls so that the intersections of orthogonal planes, having the axis of the screen as their line of intersection, with the screen are different, whereby said screen has a shape different from a surface of revolution and the equipotential lines of the electric field established between cathode and screen when a potential difference is applied therebetween are strongly elliptical in shape.

35 45 7. A cathode-ray tuning indicator tube comprising a funnel-like, hollow, luminescent screen, a cathode arranged centrally and coaxially within the luminescent screen, and means including deflection members disposed between the cathode and screen for controlling, by its potential, the extent of fluorescence of the screen and arranged to provide two opposed fluorescent areas on the screen, said funnel-like screen having convex portions on opposed side walls so that the intersections of orthogonal planes, having the axis of the screen as their line of intersection, with the screen are different, whereby said screen has a shape different from a surface of revolution and the equipotential lines of the electric field established between cathode and screen when a potential difference is applied therebetween are strongly elliptical in shape.

40 50 8. A cathode-ray tuning indicator tube comprising a funnel-like, hollow, luminescent screen, a cathode arranged centrally and coaxially within the luminescent screen, and means including deflection members disposed between the cathode and screen for controlling, by its potential, the extent of fluorescence of the screen and arranged to provide two opposed fluorescent areas on the screen, said funnel-like screen having convex portions on opposed side walls so that the intersections of orthogonal planes, having the axis of the screen as their line of intersection, with the screen are different, whereby said screen has a shape different from a surface of revolution and the equipotential lines of the electric field established between cathode and screen when a potential difference is applied therebetween are strongly elliptical in shape.

45 55 9. A cathode-ray tuning indicator tube comprising a funnel-like, hollow, luminescent screen, a cathode arranged centrally and coaxially within the luminescent screen, and means including deflection members disposed between the cathode and screen for controlling, by its potential, the extent of fluorescence of the screen and arranged to provide two opposed fluorescent areas on the screen, said funnel-like screen having convex portions on opposed side walls so that the intersections of orthogonal planes, having the axis of the screen as their line of intersection, with the screen are different, whereby said screen has a shape different from a surface of revolution and the equipotential lines of the electric field established between cathode and screen when a potential difference is applied therebetween are strongly elliptical in shape.
